UNITED STATES PATENT OFFICE.

WILL R. SAVAGE, OF OMAHA, NEBRASKA.

VALVE.

1,154,811.

Specification of Letters Patent. Patented Sept. 28, 1915.

Application filed November 1, 1912. Serial No. 729,133.

To all whom it may concern:

Be it known that I, WILL R. SAVAGE, a citizen of the United States, and a resident of Omaha, in the county of Douglas and State of Nebraska, have invented certain new and useful Improvements in Valves, of which the following is a specification.

My invention relates to valves of the class employed for controlling the passage of fluids through pipes.

It is the object of my invention to provide in a valve of this kind a structure such that the fluid in passing through the valve will be deflected as little as possible from a straight line; to provide means by which the contacting surfaces of the valve-disk and valve-seat will tend to preserve smooth surfaces; to provide means by which the contacting parts of the valve-disk and valve-seat may be trued up or renewed readily; and to provide novel actuating means for moving the valve-disk toward and away from the valve-seat.

In the accompanying drawings, Figure 1 is a longitudinal sectional view of a valve embodying my invention, Fig. 2 is an end view of the same, Fig. 3 is a transverse sectional view taken on the plane of the line 3-3 of Fig. 1, and Fig. 4 is a detail section of the valve-disk.

In the construction shown I provide a globular body 5 which has at one end a hexagonal portion 6 threaded internally to receive a pipe, and at the other end has a cylindrical neck-portion 7. The said neck-portion is internally threaded and the annular valve-seat-body 8 is screwed into the same. The body 8 is integral with a hexagonal portion 9 which is internally threaded similarly to the body-portion 6, to receive the end of a pipe. Adjoining the valve-seat, within the body 1 and integral therewith, are several radially extending ribs 10 which form guides for the valve-disk 11. On the face of the valve-disk adjoining the seat 8 a facing-plate 12 is secured, being held thereon by means of a washer 13 and a nut 14 which is screwed onto the end of the valve-stem 15. One or more dowel-pins 16 may be provided, as shown in Fig. 4, to prevent rotary movement of the facing-plate relative to the disk. The nut 14 also serves to hold the valve-disk against a shoulder on the stem, and dowel-pins 17 may be provided to prevent relative rotation of the stem and disk. The end of the stem opposite the disk 11 has a screw-

threaded portion 18 which is screwed into a nipple 19, the nipple being concentric with the body 5 and integral therewith. The intermediate part of the valve-stem has a spiral gear 20 formed thereon, which fits revolvably within the unthreaded portion of the nipple 19, and which meshes with a similar gear 21 formed on the transverse stem 22. The transverse stem passes through a packing-gland 23, arranged in the side of the body 5 as shown in Fig. 3, and at its outer end carries a hand-wheel 24 by which it may be revolved. When the hand-wheel is turned the connection formed by the spiral gears 20 and 21 causes the valve-stem to be similarly revolved, and the threaded connection between the stem and the nipple 19 will cause the stem to move longitudinally so that the valve-disk will be moved toward or away from the seat, according to the direction of rotation of the stem. It will be noted that the connection formed by the spiral gears is such that their operation is not affected by the longitudinal movements of the valve-stem.

In opening and closing the valve the rotative movement of the disk relative to the seat as it passes into and out of contact therewith, will tend to wear the contacting surfaces evenly and thus preserve them in such condition that a tight joint may be formed between them. Should the seat become unevenly worn or corroded it may be readily removed from the valve-body and either trued up or replaced with a new one. The facing-plate 12 may also be easily removed or renewed when it becomes worn or corroded.

It will be obvious that the facing-plate may be made of a material different from that of the valve-seat or the valve-disk 11, the selection of the material employed being governed by the nature of the fluids which are to pass through the valve. It will be apparent also that the valve may be of very small size proportionately to the size of the opening through it, in practice the valve-body being smaller than that of an ordinary globe-valve of the same capacity, and the valve-opening being such that a more direct passage for the fluids is afforded than in valves of the ordinary "globe" type.

Now, having described my invention, what I claim and desire to secure by Letters Patent is:

1. In a valve, a valve body having a seat

and two bored portions each arranged within the body and spaced from the walls of the body and disposed at a right angle to each other, a stem rotatable in each bored portion, each stem having a spiral gear, said gears meshing with each other, and a valve member carried by one stem whereby upon operation of the other stem the valve member may be moved toward and away from said seat.

2. In a valve, a body having a seat, a valve for engagement with the seat, a longitudinally disposed valve stem having a low pitch threaded connection with the valve body, a spiral gear fixed on said stem in fixed relation to the low pitch thread thereof, another stem journaled in the body against longitudinal movement and disposed at a right angle to and extending past the longitudinal stem, and a spiral gear fixed on the second mentioned stem and meshing with the spiral gear on the longitudinal stem and maintained in a fixed plane at a right angle to the spiral gear on the longitudinal stem whereby, upon rotation of the second mentioned stem, the longitudinal stem and the spiral gear carried thereby are shifted backward and forward across the second mentioned stem and the valve moved toward and away from the seat and held in their different adjustments.

3. In a valve, a body having a seat, a valve for engagement with the seat, a longitudinally disposed valve stem having a low pitch threaded connection with the valve body, a spiral gear on said stem in fixed relation to the low pitch thread portion of the stem, a transverse stem journaled in the valve body at a right angle to the longitudinal stem, a spiral gear on the transverse stem in mesh with the spiral gear of the longitudinal stem and which is maintained against movement laterally of the longitudinal axis of the valve stem and the spiral gear carried thereby, whereby upon rotation of the transverse stem the longitudinal stem and the spiral gear carried thereby are moved forward and backward across the transverse stem and the valve moved toward and away from said seat and held by the low pitch thread connection with the body in its adjusted positions.

4. In a valve, a body having a seat, a disk adapted for engagement with said seat, a valve stem carrying said disk and mounted for rotatable and longitudinal movement to shift the disk toward and away from the seat, and means to rotate the same to shift the disk to open and closed positions and to coöperate with the mounting means of the disk-carrying stem to assist the latter in holding the disk in open and closed positions.

5. In a valve, a body having a seat, a disk adapted to engage the seat, a valve stem car-

rying said disk and provided with a threaded portion engaging a similarly threaded portion of the body, a driving stem journaled in the body, and means between the stems coacting with the screw threaded connection between the valve stem and body to effect rotation of the valve stem, and a consequent movement of the disk toward and from said seat and assist the threaded connections between the valve carrying stem and the body to hold the disk in adjusted positions.

6. In a valve, a body having a seat, a disk adapted for engagement with the seat, a valve stem carrying said disk having a threaded portion engaging a similarly threaded portion of the body, a driving stem rotatably held in the valve body at right angles to the valve stem, and interengaging spiral gears connected with the respective stems, whereby rotation of the transverse driving stem will actuate the disk carrying stem and shift the disk toward and away from said seat and coact with the threaded connection between the disk-carrying stem and the body to hold the disk in adjusted position against accidental movement.

7. In a valve, a body provided with a bearing whose internal bore is screw threaded throughout a portion of its length, a stem provided with a screw threaded portion having working fit in the screw threaded portion of the bore of said bearing, a spiral gear on said stem, a driving stem journaled in said bearing, and a spiral gear immovably mounted on the driving stem constantly in mesh with the spiral gear on the driven stem, so that on rotative movement of the driving stem the driven stem is rotated and moved longitudinally by its screw threaded connection with said bearing.

8. In a valve, a valve body having an internal seat and an internal casting provided with communicating bores arranged at right angles to each other, one of said bores being arranged in coaxial relation to the longitudinal axes of the body and inferiorly threaded throughout a portion of its length, a stem provided with a spiral gear arranged adjacent the communication between said bores, said stem having a threaded portion coacting with the threaded portion of the bore, a disk carried by the said stem, and a driving stem operating in the other bore and having a spiral gear interengaging with the spiral gear of the other stem through the communication between said bores, whereby said other stem may be operated to move the disk toward and away from said seat.

9. In a valve, a valve body having an internal seat and an internal casting provided with communicating bores arranged at right

- angles to each other, one of said bores being arranged longitudinally of the body, a stem mounted in said longitudinally disposed bore and provided with a spiral gear arranged adjacent the communication between the bores, and a driving stem operating in the other bore and having a spiral gear interengaging with the spiral gear of said other stem through the communication between said bores, whereby the stem in the longitudinally arranged bore may be operated to move the disk toward and away from said seat. 35
10. In a valve, a valve body having an internal seat and two internally bored communicating portions, a stem rotatable in each bore, each stem having a spiral gear meshing with the other through the communication between said bores, a disk carried by one stem whereby upon operation of the other stem the disk may be moved toward and away from said seat. 40
15. In a valve, a body having a longitudinal opening, a stem extending longitudinally within the body and having a threaded portion engaging a similarly threaded portion of the body, a disk on said stem, a transverse stem extending into the body at right angles to the longitudinal stem and past a part thereof other than the threaded portion, and spiral interengaging gears formed on said stems and located between the disk and the threaded portion of the valve stem, so as to operatively connect them for rotative movement and permit the longitudinal movement of the threaded stem caused by its engagement with the threaded portion of the body. 45
20. In a valve, a body having a longitudinal opening, a seat at one end of the body, a longitudinal stem carrying the disk, the stem having a threaded portion engaging a similarly threaded portion of the body, a transverse stem, and interengaging spiral gears fixedly connected with said stems and located between the disk and the threaded connection of the valve carrying stem with the body, whereby rotation of the transverse stem will actuate the disk toward and away from the seat. 50
25. In a valve, a body having a seat, a valve stem having a low threaded connection with said body, a valve member carried by said stem, and means having connection with said stem and coacting with said low threaded connection between the stem and valve body to shift the same longitudinally to move said valve member toward and from said seat, said low threaded connection holding said stem in any position to which it is adjusted. 55
30. In testimony whereof I have hereunto subscribed my name in the presence of two witnesses.
